OIL CONVEYING MEMBER FOR JOURNAL BOXES

Thomas E. Newberry, Northumberland, Pa., assignor to National Malleable and Steel Castings Company, Cleveland, Ohio, a corporation of Ohio

Application August 14, 1936, Serial No. 95,985

3 Claims. (Cl. 308—86)

This invention relates to a dipper or paddle member used in lifting oil in a free oiling system for a railway journal box, and more particularly involves a novel construction of the dipper that will increase the life thereof several times over those now in service.

The dipper is usually mounted on and rotates with the journal and carries oil from a reservoir in the bottom of the box to points where it can be directed to the surfaces to be lubricated.

It has been found that in service the dipper is caused to vibrate principally by the shocks of the wheels passing over the rail joints. These rail joints are for the most part spaced at regular intervals so that when the train reaches a speed such that the period of impulses coincides with the period, or multiple of the period, of vibration of the dipper the amplitude of vibration increases and if any weak spots or points of stress concentration are present, cracks will soon appear and eventually result in fatigue of the metal and early breakage of the dipper. This was particularly true of dippers provided with flanged edges. These flanges were intended to strengthen the dipper and form a rigid structure. I have found, however, that fairly small amplitudes of vibration, because of the rigidity of the flanged design of dipper, set up localized zones of relatively high stress, causing cracks to appear that soon result in failure of the member. In addition the operation of forming the dipper flanges and bending it to the desired shape produces internal stresses in the metal which may result in additional sources of weakness.

After testing a large number of different designs of dippers, I have discovered a flangeless dipper of a novel construction that will give many times the life of the flanged or other rigidly designed dippers. My new and improved construction will be more fully discussed in conjunction with the drawings, in which:

Figure 1 is a vertical sectional view of a part of a journal box using a dipper embodying my invention.

Figure 2 is a face view of the dipper.

Figure 3 is an end view of one end only of the dipper with a portion broken out; and

Figure 4 is a view of the dipper in perspective.

In Fig. 1 there is shown a journal box 1, journal 2, and the usual bearing member 3 and wedge 4. The journal box is formed with a deepened portion 5 at the front end thereof, which constitutes a part of the oil reservoir. The dipper

6 is secured to the end of the journal by means of bolts 7. Between the bolts and the end of the journal there is positioned a washer 8 for a purpose to be later described.

Referring particularly to Figs. 1 and 4, the central or hub part of the dipper is formed with openings 9 which receive the bolts 7. On either side of the hub and outwardly of the bolt holes the dipper is bent away from the journal in sweeping curves 10 which merge into axially extending portions 11. From these latter portions the dipper is curved radially outward at each end at 12, these curves also being of substantial radii. From curves 12 the dipper extends straight outward at each end as at 13 until it reaches the curves 14 where it is bent back toward the journal to form portions 15 substantially parallel to portions 11. At the end of portions 15 it is curved radially outward at 16 to merge with the blades 17 and 18 that dip into the reservoir and carry the oil to the top of the box. As shown in Figs. 2 and 4, the two ends of the dipper are preferably of different form, the end 17 having a pair of wings 17' extending externally beyond the main body while the end 18 is preferably straight-sided and of about the same width as portion 13. Both ends have their extremities curved along an arc whose center is at the journal axis. The wing portions of the end 17 and the side edges of the end 18 are preferably bevelled, as shown at 22 and at 23, respectively.

It will be noted that portion 15 extends inward to a point where it overlies a projection 19 on wedge 4. This projection is formed with a groove 20 that conducts oil dropping from the dipper to the bearing surfaces on the brass and journal. The general shape of the dipper as above described is required in order to provide the overlap with the projection on the wedge. While I have specifically referred to curves 10 and 12 being formed on large radii, it will be understood that it is desirable to form curves 14 and 16 on as large radii as possible and still maintain the necessary clearance between the dipper and the end of projection 19. It is preferable, as clearly illustrated in Fig. 1, to make curve 10 of the largest radius of curvature with the radii of curves 12 and 14 progressively decreasing in length. The sweeping curves avoid over-stressing the metal and eliminate one of the causes of cracks in old-style dippers.

If my improved dipper were made the same width over its entire length, there would be a tendency for it to vibrate about lines drawn

through the openings 9 since the weakest sections would be at these points. It is not desirable to increase the width of the dipper over its entire extent to strengthen the weak section, for, by this means, weight would be added at a considerable distance from the center of rotation and the centrifugal force tending to straighten out the dipper would be thereby increased. Furthermore, when subjected to a shock as from a rail joint, any increase in weight at the ends of the dipper will increase the stresses resulting from the vibration of these heavier ends.

I have found that by widening the hub portion of the dipper between points radially outward of openings 9 and then joining the edges of the widened portion with the edges of the axially extending portions 11, by sweeping curves 21, that adequate strength is obtained through the bolt holes without adding weight at undesirable points. The central portion of the dipper can be said to be U-shaped with the base of the U widened, the widened portion merging into and terminating in the arms of the U.

To further assist in preventing vibration of the dipper ends about lines through the bolt holes the member 8 is positioned between the heads of bolts 7 and the outer surface of the dipper and is constructed so that its ends bear on curved portions 10. In Fig. 1 member 8 is shown extending distance a beyond the beginning of curve 10. By this means the dipper is clamped tightly against the journal and vibration normally will take place about the lines of contact between the member and dipper rather than through the bolt holes.

The improved design is more flexible than the flanged dipper, but for a given amplitude of vibration the dipper will be stressed far less than a flanged dipper vibrating the same amount. This, in combination with the sweeping curves and the decrease in width from the hub portion permits the stresses set up by vibration to be distributed uniformly over the unsupported part of the dipper.

The terms and expressions which I have employed are used as terms of description and not of limitation, and I have no intention, in the use of such terms and expressions, of excluding any equivalents of the features shown and de-

scribed or portions thereof, but recognize that various modifications are possible within the scope of the invention claimed.

What I claim is:

1. In a device of the class described a journal box having an oil reservoir at the bottom thereof, a journal extending into said box, a member on the end of said journal adapted to raise oil from said reservoir to points for delivery to said journal, means securing said member to said journal, said member having portions curved away from said journal outwardly of said securing means, and a washer element between said securing means and member, the ends of said element engaging said curved portions for clamping said member tightly against the journal. 5

2. A dipper for attachment to a railway journal for conveying oil from a reservoir to a distributing point which comprises a member formed of a sheet of metal bent to present portions in a plurality of different vertical planes, said member having a central hub portion, a pair of oil conveying ends, and intermediate portions, curved portions joining said hub portion, intermediate portions and said ends, said hub portion being of greater width than said intermediate portions, said member in side elevation presenting no surface of greater width than the thickness of said metal sheet, and means for attaching said dipper to a journal comprising an element adapted to be forced against said hub portion, the ends of said element overlying said curved portions adjacent said hub portion. 10

3. A dipper for a railway journal box comprising a flat plate having blades at the ends thereof adapted to lift oil in the journal box, said plate having a flat base portion adapted to be secured to the end of a journal, intermediate portions of lesser width than and offset laterally from said base portion and parallel thereto, said blade portions being parallel to said base portion and offset from said base an amount less than said intermediate portions, the portions joining said base and intermediate portions being gently curved throughout substantially their entire length and progressively decreasing in width from said base toward said intermediate portions. 15
